US00D881584S

(12) **United States Design Patent** (10) Patent No.: **US D881,584 S**
Porter et al. (45) Date of Patent: **** Apr. 21, 2020**

(54) **TOOTHBRUSH HANDLE**

(71) Applicant: **WATER PIK, INC.**, Fort Collins, CO (US)

(72) Inventors: **Austin Rand Porter**, Seattle, WA (US); **Taylor Elizabeth Thomas**, Seattle, WA (US); **Jeffrey Ladwig**, Seattle, WA (US)

(73) Assignee: **WATER PIK, INC.**, Fort Collins, CO (US)

(**) Term: **15 Years**

(21) Appl. No.: **29/680,862**

(22) Filed: **Feb. 20, 2019**

Related U.S. Application Data

(62) Division of application No. 29/587,868, filed on Dec. 15, 2016, now Pat. No. Des. 845,636.

CLAIM

We claim the ornamental design for a toothbrush handle, as shown and described.

DESCRIPTION

FIG. 1 is a front isometric view of a toothbrush handle.

FIG. 2 is a front elevation view thereof.

FIG. 3 is a rear elevation view thereof.

FIG. 4 is a right side elevation view thereof.

FIG. 5 is a left side elevation view thereof.

FIG. 6 is a top plan view thereof; and,

FIG. 7 is a bottom plan view thereof.

The broken lines illustrate portions of the toothbrush handle that form no part of the claimed design.

1 Claim, 4 Drawing Sheets
